(57) **CLAIM**

The ornamental design for a faucet, as shown and described.

DESCRIPTION

The file of this patent contains at least one drawing executed in color.

FIG. 1 is a front, top, and right side perspective view of a faucet;

FIG. 2 is a front elevational view thereof;

FIG. 3 is a rear elevational view thereof;

FIG. 4 is a right side elevational view thereof, the left side elevational view being a mirror image of the view shown;

FIG. 5 is a top plan view thereof;

FIG. 6 is a right side elevational view thereof, showing the socket and the ring in an exemplary orange color;

FIG. 7 is a right side elevational view thereof, showing the socket and the ring in an exemplary red color;

FIG. 8 is a right side elevational view thereof, showing the socket and the ring in an exemplary green color;

FIG. 9 is a right side elevational view thereof, showing the socket and the ring in an exemplary blue color;

FIG. 10 is a right side elevational view thereof, showing the socket and the ring lined for another exemplary orange color;

FIG. 11 is a right side elevational view thereof, showing the socket and the ring lined for another exemplary red color;

FIG. 12 is a right side elevational view thereof, showing the socket and the ring lined for another exemplary green color; and,

FIG. 13 is a right side elevational view thereof, showing the socket and the ring lined for another exemplary blue color.
